UNITED STATES PATENT OFFICE.

JAMES E. HOOKER, OF CORAL GABLES, FLORIDA.

SHINGLE.

Application filed March 5, 1927. Serial No. 173,075.

This invention relates to shingles.

An object of the invention is the provision of a shingle which may be cut from a roll of roofing paper in such a manner as to eliminate all waste, the shingle being of the lock-down type, with the locking so arranged that when the shingles are applied to a roof only one nail will be required to secure the shingle in position, thus insuring said shingle against curling, warping or becoming loosened by exposure to weather, wind and other stresses.

A further object of the invention is the provision of an economical roof covering adapted, when applied to a roof, to include a relatively large portion covered or overlapped by adjacent shingles but which will have relatively little weight per square foot of roof so that a given roof area of sheathing may be covered with comparatively few shingles.

A further object of the invention is the provision of a shingle having a plurality of slits, one being located at each of the three corners, the free corner indicating always the top of the shingle to facilitate the application of the shingles to a roof, one of the corners adjacent the flap being adapted to be nailed or secured in any crude manner to the roof whereby a plurality of the ends of the shingles will be secured in position with the nailed portion being covered by a succeeding shingle.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention is expressed in the appended claims.

45 In the drawings:

Figure 1 is a plan view of a portion of a roof covered with shingles constructed in accordance with the principles of my invention.

50 Figure 2 is a transverse section taken along the line 2-2 of Figure 1.

Figure 3 is a view in perspective of one form of the shingle.

Figure 4 is a fragmentary view in per-

spective of the shingle showing the securing means for the same,

Figure 5 is a view in perspective of a modified form of shingle,

Figure 6 is a view in perspective of a further modified form, and

Figures 7 and 8 are views in perspective of still further modifications of the shingle shown in Figure 3.

Referring to the drawings 10 designates a roof to which a shingle 11 shown in Figure 3 is applied. This shingle is either square or rectangular in shape and is provided with slits 12, 13 and 14 at three corners to provide, respectively, the interlocking flaps 15, 16 and 17. The corner 18 is free of a slit and forms the upper end of the shingle which is always covered by succeeding and superimposed shingles. Furthermore, the end 18 indicates at all times the disposition of the shingle when applied to a roof and, therefore, facilitates the ready positioning.

Referring more particularly to Figure 1 it will be seen that the shingles are so applied that they simulate a so-called diamond-shape in that the free end is disposed in substantial vertical alignment with the end or flap 16 with the corner 18 always pointing towards the ridge pole of the roof. The shingles 11 are applied along the lower edge of the roof and cut off along the line indicated at 19 or instead of being cut off the lower ends of the shingles are bent under and secured if desired. A second row of shingles is then applied to the roof with their lower edges overlapping the upper edges of a pair of adjacent shingles of the first row, as shown at 20. The flaps 15, 16 and 17 aid in positioning the shingles in their proper place without the aid of a chalk line since the flaps 15 and 17 of one shingle overlap with the similarly-formed and adjacent flaps of an adjacent shingle.

As shown in Figure 2 a portion 21 of each shingle which is adjacent the flap 17 is nailed to the roof either by the usual enlarged headed nails or by staples 22. This staple or nail penetrates at least three shingles and in co-operation with the interlocking flaps form the sole means for securing the shingles in associated relation and for securing the shingles to the roof.

Referring more particularly to Fig. 5 a shingle 23 is shown having slits 24, 25 and

26 formed at right angles to the respective edges and with a lateral straight slit 27 in communication with the slits 24 to 26, inclusive, and being inclined towards an opposite edge which forms a right angle with the edge through which the main slit has been made.

5 In the shingle 28 shown in Fig. 7 the slits 29 which cut through the three edges of the shingle have curved extensions 30 directed towards another edge of said shingle. In Figure 6 a shingle 31 is disclosed having slits 32 located at right angles to the edge through which the cut has been made and 10 right angularly disposed cuts 33 are provided at the extreme inner ends of the cuts 32 and providing flaps 34.

The shingle 35 shown in Fig. 8 has cuts 36 formed at right angles to the edge through 20 which the slit is formed and is provided at the extreme inner ends with circular passages 37. The cuts 36 form interlocking flaps 38 at three corners of the shingle. The remaining corner 39 forms the upper end of 25 the shingle and is adapted to form an indicator for the proper disposition of the shingles when being applied to the roof.

The shingles shown in Figs. 5, 6 and 7 provide an additional locking means for the 30 various flaps and therefore a more secure roof. All of the shingles, however, are secured by means of staples or nails as indicated.

I claim:

25 1. A shingle comprising a basically square sheet of roofing material having cuts at three corners to provide interlocking flaps

for adjacent shingles when applied to the roof, each cut extending inwardly from one side edge towards an opposite edge. 40

2. A shingle formed of a square sheet of roofing material being cut at three corners to provide a plurality of interlocking flaps, the remaining corner which is free of a cut providing an indicator for determining the proper position of the shingle on a roof, the portion of the shingle adjacent one cut being adapted to be nailed to the roof, each cut extending inwardly from one side edge towards an opposite edge. 45 50

3. A shingle formed of a square sheet of roofing material being provided with a cut at three corners to form an interlocking flap at said corners, said shingles being provided with an additional cut at the inner end of 55 the first-mentioned cuts with the second-mentioned cut extending towards an edge which forms a right angle through which the first-mentioned cut is made.

4. A device of the character described 60 comprising a plurality of shingles, each shingle being square shaped and formed of roofing material, each shingle having a cut at three corners to form flaps interlocked with flaps of associated shingles, the end of the 65 shingle which is free of the cut projecting outwardly from the group of shingles and covered by a shingle having overlapping engagement with the adjacent edges of associated shingles, and means for securing one 70 corner of a shingle to the roof, each cut extending inwardly from one side edge towards an opposite edge. 75
